RECIPROCATING ELECTROMAGNETIC
MOTOR

Harland L. McHenry, Sayre, Pa., assignor to
Bendix Aviation Corporation, a corporation of
Delaware

Application September 18, 1947, Serial No. 774,725

7 Claims. (Cl. 172—126)

1

The present invention relates to a reciprocating electromagnetic motor for pumps and the like and more particularly to the controlling mechanism therefor.

Various forms of electromagnetic motors incorporating a reciprocating actuated element have been devised in which a solenoid is used as an actuator, and the intermittent energization of the solenoid effectuated by contacts which are controlled in various ways by the actuated element. When such control has been by magnetic means, involving variations in air gaps in a magnetic circuit, difficulties have been encountered in obtaining adequate contact pressure and reliability of operation.

It is an object of the present invention to provide a novel electromagnetic motor which is simple in construction and efficient and reliable in operation.

It is another object to provide such a device including a magnetic control of the actuating contacts.

It is another object to provide such a device in which the opening and closing of the actuating contacts is by means of branch magnetic circuits which are in shunt with each other whereby the weakening of the flux through one branch causes an increase in flux in the other branch, thus insuring positive and effective actuation of the contacts.

Further objects and advantages will be apparent from the following description taken in connection with the accompanying drawing, in which:

Fig. 1 is a substantially mid-sectional view of an electromagnetic pump structure incorporating a preferred embodiment of the invention; and

Fig. 2 is a section taken substantially on the line 2—2 of Fig. 1.

In Fig. 1 of the drawing, there is illustrated a cylinder 1 of non-magnetic material in which a magnetic piston 2 is slidably mounted. A spring 3 is arranged to urge the piston toward the upper end of the cylinder, and a solenoid 4 surrounding the cylinder is effective when energized to retract the piston against the force of the spring 3.

Circular pole pieces 5 and 6 surround the cylinder 1 adjacent the ends of the solenoid 4, and a casing 7 of magnetic material is arranged to enclose the entire structure and to furnish a return path for the flux of the solenoid.

Means for energizing the solenoid to actuate the pump are provided comprising a battery 8 grounded at 9 and connected through a switch 11 and lead 12 to one terminal of the solenoid.

2

The opposite terminal of the solenoid is connected by a lead 13 to a fixed contact 14 (Fig. 2) and a movable contact 15, which is grounded as indicated at 16, is adapted to be brought into engagement with the fixed contact 14 to complete the energizing circuit for the solenoid 4.

Means for actuating the contact 15 to cause reciprocation of the piston 4 is provided comprising an electromagnet indicated by numeral 17. Electromagnet 17 is composed of a stationary part 18 and a movable part 19 pivoted thereto as indicated at 21. The parts 18, 19 are continuously magnetized during actuation of the pump by means of a coil 22 connected at one end to the battery lead 12, and having its other end grounded as shown at 23.

The stationary part 18 of the electromagnet 17 is formed with a block 24 of magnetic material conforming interiorly to the outer wall of the cylinder 1, and exteriorly to the inner wall of the casing 7. The free end of the movable part 19 of the electromagnet is also formed as a block 25 the inner end of which conforms to the outer surface of the cylinder 1 and is located substantially diametrically with respect to the block 24. The block 25 is formed at its outer end with a convex surface 26 located adjacent the inner wall of the casing but spaced inwardly therefrom. A curved abutment member 27 of non-magnetic material limits the travel of the block 25 outwardly toward the wall of the casing.

The movable contact 15 is carried by an arm 28 fixed as indicated at 29 to the block 25 so that pivotal movement of the block 25 and part 19 of the electromagnet causes the contact 15 to move into and out of engagement with the fixed contact 14.

In the operation of this device, starting with the parts in the positions shown in Figs. 1 and 2, closure of the manual switch 11 causes energization of the electromagnet 17. Since the piston 2 is at the upper end of its stroke, it closes the gap between the magnetic blocks 24, 25 except for the thickness of the walls of cylinder 1, so that the flux of the electromagnet 17 flows from one block to the other through the piston 2 causing the block 25 to be strongly attracted to the piston, thus holding contact 15 in engagement with contact 14. The solenoid 4 is thus energized from the battery 8 whereby the piston 2 is retracted downward against the spring 3 until it is drawn away from the zone of magnetic blocks 24, 25. When this happens, the air gap formed between the magnetic blocks 24, 25 becomes greater than the gap between the surface 26 and the

interior of the casing 7. The flux of electromagnet 17 thereupon is diverted from the direct path through the cylinder and flows through the casing 7 and across the gap to the surface 26 of magnetic block 25 whereby the latter is attracted outwardly toward the casing until stopped by the spacer 21, thus opening contacts 14, 15.

When the solenoid 4 is thus deenergized, the spring 3 becomes effective to actuate the piston 2 which moves upwardly until its upper end again bridges the space between the magnetic blocks 24, 25. The reluctance of the shunt magnetic path from block 24 through the piston to block 25 is thereby lowered so that most of the flux follows this path. The block 25 is thus attracted inwardly until it engages the cylinder 6, whereby the contacts 14, 15 reclose, and the operation is repeated.

Although but one embodiment of the invention has been shown and described in detail, it will be understood that other embodiments are possible and changes may be made in the form and arrangement of its parts without departing from the spirit of the invention as defined in the following claims.

What is claimed is:

1. In an electromagnetic reciprocating motor, a cylinder of non-magnetic material, a piston of magnetic material slidably mounted therein, a spring for actuating the piston in one direction, a solenoid arranged when energized to move the piston against the force of the spring, means for controlling the energization of the solenoid including a fixed contact, a movable contact, a magnetized member carrying said movable contact pivotally mounted for movement toward and away from the cylinder, means for completing a circuit for the flux of said magnetized member including the piston in the cylinder and means for providing a shunt path for said flux which does not include said piston.

2. An electromagnetic motor as set forth in claim 1 in which said shunt path includes an air gap which is substantially greater than twice the thickness of the cylinder wall, but less than the diameter of the piston.

3. An electromagnetic motor as set forth in claim 2 in which the shunt magnetic circuit is composed of magnetic material except for said air gap and the pivotal mounting of the magnetized member.

4. In an electromagnetic reciprocating motor, a cylinder of non-magnetic material, a piston of magnetic material slidably mounted therein, a spring for actuating the piston in one direction, a solenoid arranged when energized to move the piston against the force of the spring, a casing of magnetic material surrounding the solenoid, means for controlling the energization of the solenoid including a fixed contact, a movable contact, a magnetized member carrying said movable contact pivotally mounted for movement toward and away from the cylinder, means for completing a

circuit for the flux of said magnetized member including the piston in the cylinder, and a shunt path for said flux including said casing and an air gap between the casing and the magnetized member.

5. In an electromagnetic reciprocating motor, a cylinder of non-magnetic material, a piston of magnetic material slidably mounted therein, a spring for actuating the piston in one direction, a solenoid arranged when energized to move the piston against the force of the spring, means for controlling the energization of the solenoid including a fixed contact, a movable contact, a magnetized member carrying said movable contact pivotally mounted for movement toward and away from the cylinder, means for completing a circuit for the flux of said magnetized member including a block of magnetic material in contact with and conforming to the interior of the casing and the exterior of the cylinder, and connected to the pivoted end of the magnetized member, the free end of the magnetized member conforming with and adapted to engage the exterior of the cylinder substantially opposite said block.

10 25 6. An electromagnetic motor as set forth in claim 5 in which said free end of the magnetized member also has a pole piece extending toward the wall of the casing.

7. In an electromagnetic reciprocating motor, a cylinder of non-magnetic material, a piston of magnetic material slidably mounted therein, a spring for actuating the piston in one direction, a solenoid arranged when energized to move the piston against the force of the spring, means for controlling the energization of the solenoid including a fixed contact, a movable contact, a magnetized member carrying said movable contact pivotally mounted for movement toward and away from the cylinder, means for completing a circuit for the flux of said magnetized member including the piston in the cylinder and means for providing a shunt path for said flux which does not include said piston; in which the magnetized member is shaped to conform to the cylinder, and when in contact therewith, the magnetic circuit through the piston is completed through magnetic material except for the walls of the cylinder and the pivotal mounting of the magnetized member.
